A. J. GREENWICH

MARCEL WATER WAVER

Filed May 1, 1926

Patented Aug. 2, 1927.

1,637,816

UNITED STATES PATENT OFFICE.

ANNA J. GREENWICH, OF CHICAGO, ILLINOIS, ASSIGNOR OF ONE-HALF TO WALTER M. ROEWER, OF CHICAGO, ILLINOIS.

MARCEL WATER WAVER.

Application filed May 1, 1926. Serial No. 105,940.

This invention relates to a marcelling device for hair and more particularly to an improved Marcel water waver adapted to be removably engaged in a strand of hair which 5 has been dampened with water, after which the device is adjusted to warp the strand of hair transversely to effect a Marcel wave which is adapted to remain in the hair, which is permitted to dry with the waver in 10 position, thereby affording a means whereby a plurality of improved Marcel water wavers may be used adjacent one another to produce a marcelling effect in a strand of hair which is adapted to remain in effect a considerable 15 length of time.

It is an object of this invention to provide an improved Marcel water waver adapted to be removably engaged in a strand of hair and having portions thereof adjustable longitudinally with respect to one another to 20 effect a transverse wave in a strand of hair.

It is also an object of this invention to provide a Marcel water waver adapted to be engaged in a strand of hair and then adjusted to cause comb members to be shifted longitudinally with respect to one another to cause a portion of the strand of hair engaged between the comb members to be shifted transversely to produce a Marcel wave which 30 is permitted to dry while the Marcel waver is in position so that the wave produced is more or less permanent in effect.

It is a further object of this invention to provide Marcel water wavers adapted to be removably engaged in a wet strand of hair adjacent one another, with each of said wavers constructed with shiftable combs so that portions of the strand of hair are adapted to be marcelled transversely of the strand 40 to effect a substantially flat Marcel wave in the strand of hair before removing the wavers after the hair has dried.

It is an important object of this invention to provide Marcel water wavers adapted to be removably engaged in a strand of hair in a substantially parallel relation with each of said wavers, embracing a pin member having a yoke or bracket pivotally engaged thereon to the ends of which comb members 50 are pivotally connected to permit the same to be removably engaged on the pin member and then shifted longitudinally of the pin member and of each other to cause a substantially flat Marcel wave to be produced 55 in a strand of wet hair which when dried is

adapted to have the wavers removed, leaving a completed substantially flat Marcel wave in the strand of hair.

Other and further important objects of this invention will be apparent from the disclosures in the specification and the accompanying drawings.

This invention (in a preferred form) is illustrated in the drawings and hereinafter more fully described.

On the drawings:

Figure 1 is a profile view of a lady's head, a strand or section of the hair on one side of the head having a plurality of improved Marcel water wavers removably engaged thereon and embracing the principles of this invention.

Figure 2 is an enlarged fragmentary view of a strand of hair showing portions of a pair of Marcel water wavers in position to produce a Marcel wave effect in the hair.

Figure 3 is a fragmentary top plan view of the Marcel water waver embodying the principles of this invention.

Figure 4 is a top plan view of the Marcel water waver showing the parts shifted into a Marcel producing position.

Figure 5 is an enlarged side view of the Marcel water waver when in the adjusted position illustrated in Figure 4.

Figure 6 is a detail section taken on line VI—VI of Figure 4.

Figure 7 is a fragmentary detail section taken on line VII—VII of Figure 3.

Figure 8 is a fragmentary detail section taken on line VIII—VIII of Figure 4.

As shown on the drawings:

The reference numeral 1 indicates the head of a young lady having bobbed hair 2 with a strand of hair on one side of her head indicated by the reference numeral 3. Removably engaged in the strand of hair 3 are a plurality of adjacently disposed improved Marcel water wavers embodying the principles of this invention and each comprising a curved or arc-shaped pin 4 made of metal or other suitable material having a point at one end thereof and a flattened head 5 on the other end thereof. Integrally formed on the upper face of the pin head 5 is a detent or hump 6 for a purpose herein-after more clearly described. The flat headed end 5 of the pin 4 is pivotally engaged on a pivot pin 7 which is pivotally engaged through an aperture in the middle portion 116

of a yoke or turn bar 8 having a stop flange 9 formed at right angles along the outer margin thereof. The yoke 8 is provided with a plurality of spaced detents 10 on both sides of the middle portion thereof. As illustrated in Figure 7, a spring washer 11 is engaged on the pivot pin 7 below the pin head 5 to afford a means whereby the detent 6 is adapted to be resiliently engaged between a pair of the detents 10 when the yoke member 8 is pivotally swung about the pivot pin 7 as illustrated in Figure 4. A spacing ring or washer 12 is provided on the pivot pin 7 between the flat head 5 of the pin 4 and below the yoke 8.

Pivotally engaged through an aperture in each end of the yoke bar 8 is a rivet or pin 13 to which is engaged a connecting link 14. Pivotally connected to each of the connecting links 14 is an arc-shaped comb 15 having a hook member 16 engaged on the inner side of the free end thereof.

The operation is as follows:

As clearly illustrated in Figure 1, a plurality of the improved Marcel waters wavers are adapted to be simultaneously used to produce the desired substantially flat Marcel water wave in the section of the hair engaged by the improved wavers. The strand or section of hair which is to be marcelled is damped with water and the pin member 4 is then inserted underneath the strand of hair adjacent the scalp. One of the comb members 15 is then engaged on top of the hair and moved through the hair until said comb member is brought adjacent one side of the covered pin 4. The hook member 16 of the comb is then removably hooked onto the pin member 4. In a similar manner, the second comb member 15 is engaged in the hair and moved toward the opposite side of the covered pin 4. The hook member of the second comb is then also engaged on the pin 4. This arrangement positions a portion of the hair beneath the combs and over the intermediate pin member as illustrated in Figures 1 and 2. With one of the improved Marcel water wavers in position, the two combs 15 are shifted longitudinally with respect to one another in opposite directions with respect to the pin 4. This causes the yoke member 8 to pivot on the end of the pin 4 and moves the detent 6 into locking engagement between two of the detents 10 of the yoke member. The pin is thus resiliently held in a locked position with both of the combs offset with respect to one another as clearly illustrated in Figure 4. This shifting of the combs 15 in opposite directions with respect to the intermediate pin 4 causes the portion of the hair engaged over the pin member 4 and between the combs to be shifted laterally as indicated in Figure 2 so that the hairs in the confined section are disposed at an angle. A second water waver

may now be placed in position similar to the first and after the lock of hair has been engaged, the combs are shifted with respect to one another so that the section of the hair is shifted in a transverse direction at an angle substantially parallel to the section confined between the combs of the first waver. This shifting of the hair transversely between the combs causes the hair between a pair of Marcel water wavers to be inclined in a direction opposite to the inclined direction of the hair between the combs of the respective wavers. This arrangement causes the strand of hair to be waved in a transverse direction back and forth between the various wavers, thereby retaining the section of the hair clamped by means of the adjacently disposed Marcel water wavers. With a plurality of water wavers in position as shown in Figures 1 and 2, the hair is permitted to gradually dry, after which the Marcel water wavers are removed from the hair, leaving the section of the hair with a substantially flat marcel therein.

The marcelling of the hair as above described is produced without the aid of heat so that no damage is done to the hair. The wavers may be readily placed in position and when in position are adapted to have the combs shifted in opposite directions to produce the transverse wave effect desired.

The improved Marcel wavers may be applied to the hair when the same is dry before a person goes in bathing, for instance, and left in position after a person comes out of the water until the hair is dry. The wavers may then be removed, thus leaving the hair properly marcelled.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A Marcel water waver comprising a pin member, a yoke pivotally mounted on one end thereof, detents on said yoke and on said pin member to permit the yoke to be removably locked in an adjusted position with respect to said pin member, a plurality of links movably connected to the ends of said yoke, combs pivotally engaged on said links, and hook members on said combs adapted to be removably engaged on said pin.

2. A Marcel water waver comprising a pin, a yoke pivotally mounted thereon, combs pivotally connected to said yoke, and means on said combs to permit the same to be slidably engaged on said pin.

3. A Marcel water waver comprising a pin member, a cross member pivotally mounted thereon, and combs suspended from

said cross member adapted to be removably engaged on said pin and shifted longitudinally with respect thereto.

4. A hair marcelling device comprising an intermediate member adapted to be engaged below a strand of hair, a cross member pivotally mounted on said intermediate member, means for locking said intermediate member in an adjusted position with respect to said cross member, a plurality of combs movably engaged on said cross member on opposite sides of said intermediate member, and hook members on said combs adapted to be removably engaged on said intermediate member to permit the combs to be shifted longitudinally with respect to one another in opposite directions and with respect to said intermediate member so that the portion of the hair engaged over said intermediate member and between said combs is adapted to be shifted laterally to produce a Marcel wave effect in the hair.
5. A Marcel water waver comprising a pair of combs, a pin intermediate said combs, and means permitting said combs to be shifted in opposite directions with reference to said pin.
6. A Marcel water waver comprising a pair of comb members, simultaneously shiftable in opposite directions, a pin member pivotally mounted therebetween, and means for locking the comb members in their adjusted offset positions.
7. A Marcel water waver comprising a pair of movable comb members, a supporting pin member pivotally mounted therebetween, and locking means for holding said comb members locked in their adjusted positions to said pin member.
8. A Marcel water waver comprising a pair of shiftable comb members, a supporting pin member mounted therebetween, to afford a means for holding the entire waver in place on a person's head and locking means for holding said comb members in an adjusted position on said pin member.
9. A Marcel water waver comprising a

cross bar, a pin pivoted thereon, a pair of combs on opposite sides of said pin and pivotally connected to said cross bar, co-acting locking means on said cross bar and on said pin adapted to hold the comb members in an adjusted position with respect to said pin.

10. A Marcel water waver comprising a supporting member, a pair of combs and a pin member pivotally connected to said supporting member, and means on said comb members adapted to be removably engaged on said pin member.

11. A Marcel water waver comprising a pair of combs, a pin positioned therebetween, and means for engaging said pin to permit the combs to be simultaneously shifted in opposite directions longitudinally of said pin.

12. A Marcel water waver comprising a pair of connected combs adapted to be shifted simultaneously in opposite directions longitudinally with respect to one another and an intermediate hair supporting member.

13. A Marcel water waver comprising a pair of connected combs adapted to be shifted longitudinally with respect to one another, and means for pinning the combs in position and permitting longitudinal adjustment with respect to the pinning means.

14. A hair waver comprising a hair engaging member, and means movably connected to one end thereof adapted to engage the hair on opposite sides of said member and also engage the other end of said member to hold the hair waver in place.

15. A hair waver comprising a member adapted to be engaged beneath a strand of hair, and means pivoted on one end thereof adapted to be engaged above said strand of hair on opposite sides of said member and be removably connected to the other end of said member.

In testimony whereof I have hereunto subscribed my name.

ANNA J. GREENWICH.
